STILT

Franklin J. Curtis, Washington, Pa.

Application July 8, 1935, Serial No. 30,370

8 Claims. (Cl. 272—70.1)

This invention relates to an improved stilt, and seeks among other objects, to provide a device of this character which may be regulated as to height so that a person learning to walk on stilts 5 may begin at a low level and gradually increase the height of the stilts.

Another object of the invention is to provide a stilt, the height of which may be adjusted with the utmost facility and which, after adjustment, 10 will remain in set position without danger of displacement.

A further object of the invention is to provide a stilt having a pawl engageable with a rack for retaining the stilt in desired position, said pawl 15 being retractible by a lever for permitting ready change in adjustment.

A further object of the invention is to provide a stilt having a tubular member which is formed with graduations so that various heights of the 20 stilt will be indicated.

And a still further object of the invention is to provide a stilt having a resilient strap which is adapted snugly to receive a shoe and which strap is adjustable for clamping the shoe in place on 25 the stilt.

Other and incidental objects of the invention not specifically mentioned in the foregoing will be apparent as the description of the invention proceeds.

30 My invention is illustrated in the accompanying drawing wherein:

Figure 1 is a side elevation showing my complete stilt and being partly broken away and shown in section.

35 Figure 2 is an enlarged fragmentary vertical sectional view of the central portion of the stilt and showing the rack, pawls, and strap employed.

Figure 3 is an enlarged horizontal sectional view on the line 3—3 of Figure 2, looking in the 40 direction indicated by the arrows.

Figure 4 is an enlarged horizontal sectional view on the line 4—4 of Figure 2, looking in the direction indicated by the arrows.

Referring now more particularly to the accompanying drawing, wherein like numerals of reference indicate like parts throughout the several views, the numeral 1 indicates a shank which is preferably formed from metal pipe and which may be either round or rectangular in cross section. Formed in the shank at its lower end portion are graduations 2 which may be in inches and fractions for indicating the height of the body, to be described hereinafter, upon the shank. Carried on the lower end of the shank is a foot 3 55 which is gradually enlarged toward its lower end

and is provided with an axial socket 4. A shoe 5, preferably formed from rubber, is fitted about the foot and is tapered toward its upper end so that said shoe will be retained on the foot. The bottom of the shoe is formed with an anti-skid tread 6 and, interiorly of the shoe and rising from the bottom thereof, is a projection 7 which is adapted to fit in the socket 4 in the foot. The shoe is formed preferably of rubber of medium hardness and will serve to provide a good gripping surface for the lower end of the stilt.

Formed in the shank 1 throughout its central portion at one side thereof are teeth defining a rack 8. As best seen in Figures 3 and 4 of the drawing, the shank is shown as being square in cross section but, if desired, the shank may be round or any other preferred shape.

Normally surrounding the shank 1 and shiftable thereon is a stilt body 9 which is preferably formed of medium weight metal and is of a shape 20 to conform to that of the shank. The stilt body 9 comprises a tubular section 10 which normally surrounds the shank throughout the major portion of its length and is adapted to project therefrom. Formed integral with the tubular section 25 10 near its lower end and projecting laterally therefrom is a stirrup or foot plate 11 which is adapted to receive the foot of the user. Connecting the outer end of the stirrup with the lower end portion of the section 10 is a diagonally disposed integral bracing arm 12 which is upwardly directed near its outer end to define a casing 13. It should be understood, of course, that the 30 stirrup, brace and tubular section are preferably cast as a single unit.

Associated with the stirrup is an arcuate resilient, preferably metal, securing strap 14 which terminates in a straight downwardly projecting tongue 15 having rack teeth 16 thereon. Carried at the under side of the securing strap is a pad 17 of preferably soft material. The pad 17 is retained in place by means of rivets, bolts, or the like. The securing strap is pivotally connected to the tubular section 10 near the junction of the stirrup 11 by means of a pin 18 which passes 40 through the section and stirrup.

As best seen in Figure 2 of the drawing, the interior of the stirrup 11 is hollow and an opening 19 leads from the interior of the section 10 to the interior of said stirrup. Mounted in the stirrup at the end adjacent the section 10 is a relatively large latch member or pawl 20 which is formed with a bill 21 of a shape to selectively engage with the rack teeth 8. The latch member is also formed with an arcuate lower wall 22 50 55

terminating in a projection 23. A pivot pin 24 swingingly connects the pawl with the stirrup therein. Extending transversely of the stirrup medially of its length is a web 25 and closing the bottom of the stirrup is a latch plate 26 which is secured in position at the under side of the stirrup by means of a screw 27. A screw 28 locks the inner end of the latch plate to a flange 29 which is formed on the tubular section 10. Carried within the stirrup and mounted on the plate 26 is an actuating lever 30 having one end portion thereof adapted partially to overlie a finger socket 31 formed in the plate 26. The latch member is oblique angular in shape and is provided with a relatively thick inner end portion 32. As will be seen in Figure 2, the plate 26 is relatively thick centrally thereof so as to permit the formation of the socket 31. A pin 33 pivotally mounts the latch member 32. When it is desired to shift the pawl 20 out of engagement with the teeth 8, it is only necessary to engage the finger nail within the socket 31 beneath the latch member 30 and swing said latch member up from the plate along the arcuate wall 22 of said pawl into engagement with the projection 23 thereon. As soon as the pawl has been disengaged from the tubular section, the inner shank and stilt body may be shifted independently to permit the stilt body to assume different heights.

Carried at the opposite end of the stirrup is a relatively small pawl 34 which is adapted to project through an opening 35 and engage selectively the rack teeth 16 of the tongue 15. The pawl 34 is pivotally mounted within the stirrup by means of a pin 36 and is provided with a projection 37 and an arcuate inner wall 38. Swingingly mounted within the plate 26 at the end opposite the latch member 30, is a latch member 39 which is pivotally mounted in the plate 26 by a pin 40 and is adapted to have its inner end swing along the wall 38 into engagement with the projection 37 for permitting rearward shifting movement of the pawl and consequent retraction of said pawl from the teeth 16. After retraction of the pawl, of course, the strap 14 may be shifted for varying the adjustment thereof. Suitable coil springs 41 are engaged about the pins 33 and 40 and are adapted for normally retaining the latch members in operative position. As in the case of the first mentioned latch member, the outer end portion of the latch member 39 is adapted to project into a finger socket 42 for permitting ready engagement of a finger nail therebeneath so that the latch member may be readily shifted.

Normally fitting in the upper end portion of the stilt body is a removable top portion or handle 43 which is reduced near its lower end to define a shank 44. Formed in this shank is a pair of vertically spaced transversely extending openings 45 in which are mounted small coil springs 46. Ball friction latches are carried at each of the openings and are normally maintained in engagement with the inner surface of the stilt body 10 by the coil springs 46, so that the handle will normally be retained in position in the stilt body.

In use, the stilt body may be adjusted on the shank merely by retracting the pawl from the rack teeth and shifting said stilt body with respect to the shank a suitable distance, as indicated by the graduations on the shank. After this has been done, a foot is inserted above the stirrup and the strap 14 forced downwardly until it engages the foot with sufficient pressure to retain the foot in position on the stirrup. The tongue 15 may then be forced downwardly within the

casing 13 the desired distance to accomplish this result. When it is desired to shift the strap 14 it is only necessary to shift the latch member 39 for retracting the pawl 34 from the opening 35 so that the tongue may be shifted within the 5 casing 13.

The device is characterized by the fact that but few working parts are employed. It will thus be seen that the device will not easily become broken under hard usage, and may be manufactured cheaply in large quantities to retail at an attractive figure. Furthermore, as my improved stilt is adjustable it provides an ideal arrangement for persons wishing to learn to walk on stilts for the reason that the height of the stilts may be 15 raised gradually so that the person using them may become used to the different heights.

Attention is directed to the fact that, if desired, my improved stilt may be taken down for shipment. It may be packaged in an attractive carton which will be convenient to handle and which will be light in weight.

Having thus described the invention, what I claim is:

1. A device of the class described having a shank adapted for engagement with a supporting surface, a stilt body associated with the shank and having a stirrup, means carried by the stirrup and engageable with the shank for locking the stilt body and shank in desired relative positions, a resilient strap carried by the stirrup for clamping a shoe on said stirrup and a latch carried by the stirrup for locking said strap.

2. A device of the class described including a shank having a foot provided with a shoe adapted to engage a supporting surface, a stilt body carried by the shank and provided with a stirrup, resilient strap means carried by the stirrup for securing a shoe thereon, retractable means within the stirrup opposite from the stilt body for retaining said resilient means in a set position, and means within the stirrup for permitting adjustment of the stilt body with respect to the shank.

3. A device of the class described including a shank, a stilt body slidable on the shank, said body having a stirrup, a resilient strap carried by the body above the stirrup and being adjustable for securing a shoe thereon, a pawl carried in the stirrup and engageable through the body with the shank for locking the body in a desired position upon the shank, a latch plate closing the bottom of the stirrup, means adapted for swinging the latch member out of engagement with the shank, a pawl carried in the opposite end of the stirrup and engageable with the strap, and means carried by the latch plate and adapted for shifting said pawl out of engagement with the strap for permitting adjustment of said strap.

4. A device of the class described including a shank having a foot thereon, a shoe carried by the shank, said shank being provided with teeth defining a rack, a stilt body slidable on the shank and having a stirrup, a latch member carried by the stirrup and adapted for selective engagement with the teeth of the rack for locking the stilt body and shank as a unit, means for shifting the latch member out of engagement with the teeth for permitting relative shifting movement of the shank and the stilt body, a strap carried by the stirrup and having a tongue formed with rack teeth, a pawl engageable with the rack teeth on the tongue for locking the strap and tongue in a desired adjusted position, and means engageable with the pawl for releasing the tongue and permitting adjustment of the strap.

5. A device of the class described including a shank having a foot thereon, a shoe carried on the foot, said shank having at one side thereof teeth defining a rack, a stilt body carried on the shank and having a stirrup formed integral therewith, a bracing arm carried by the stilt body and terminating in a casing at the free end of the stirrup, retractible means carried within the stirrup for connecting the stilt body and shank at a desired position along the length of the shank, said means engaging the rack teeth, a strap carried by the stirrup thereabove and having a depending tongue normally carried within the casing, a pad carried by the strap, a pawl carried by the stirrup and adapted to project through the casing into engagement with the tongue for retaining the strap in a desired adjusted position, and a latch member carried by the stirrup and engageable with the pawl for retracting said pawl and permitting movement of the tongue.

6. In a stilt, a shank, a stilt body slideable on the shank and having a stirrup, a resilient strap carried by the stirrup and having rack teeth, a pawl engageable with the rack teeth for locking

the strap and teeth in a set position, and means engageable with the pawl for releasing the strap and permitting adjustment of the strap.

7. In a stilt, a shank, a stilt body slideable on the shank and having a stirrup, a resilient strap carried by the stirrup and having a tongue provided with rack teeth, a pawl engageable with the rack teeth for locking the strap and tongue in a desired position, and a latch member engageable with the pawl for releasing the tongue and permitting adjustment of the strap.

8. In a stilt, a shank having teeth defining a rack, a stilt body carried by the shank and having a stirrup, a latch plate carried by the stirrup, a latch member adapted for selective engagement with the rack teeth for locking said body and the shank as a unit, said latch member having a projection and an actuating lever carried by the latch plate and having a relatively thick end portion adapted for engagement with the projection on said latch member for retracting said latch member whereby sliding movement of the stilt body on said shank may take place.

FRANKLIN J. CURTIS.
